UNITED STATES PATENT OFFICE.

BENJAMIN F. RUBEL, OF CHICAGO, ILLINOIS.

TRUNK.

SPECIFICATION forming part of Letters Patent No. 653,889, dated July 17, 1900.

Application filed September 29, 1897. Serial No. 653,447. (No model.)

To all whom it may concern:

Be it known that I, BENJAMIN F. RUBEL, a citizen of the United States, residing at Chicago, Cook county, Illinois, have invented a new and useful Improvement in Trunks, of which the following is a specification.

The object of my invention is to provide for protecting a trunk, sample-case, or similar construction, especially when handled roughly, by the use of a yielding cushion of peculiar construction at the corners thereof; and the invention consists in the features and combinations hereinafter described and claimed.

In the accompanying drawings, Figure 1 is a perspective view of one of the corners of a trunk provided with my improved protecting cushion; Fig. 2, an elevation or perspective view of the protecting cushion; Fig. 3, a perspective view of the inner plate adjacent to the wall of the trunk; Fig. 4, a sectional view taken on line 4 of Fig. 1, and Fig. 5 a sectional view showing a modified form of cushion and attachment.

Although attempts have been made to use yielding protecting devices at the corners of trunks, they have thus far been unsuccessful and never came into general use. As trunks are now constructed, therefore, it is usual to provide a solid metallic protecting device instead of a yielding protecting device at each corner; but such solid device, not possessing any giving or yielding quality, is incapable of receiving or taking up the jar or shock caused by falling, and consequently incapable of protecting the trunk against injury from falling, whether this happens through carelessness, rough handling, or other causes. The special object of my invention is to obviate or remove this objection.

In making my improved trunk, sample-case, or similar construction A, I provide a yielding cushion B, preferably of rubber, and apply the same to each corner, securing it in place by means of metallic plates fitting over wings b, extending therefrom. There are two metallic plates, an outer metallic plate C and an inner metallic plate C', and the wings of the yielding cushion are inserted between these plates or some part thereof and firmly secured and held in place by bolts or rivets D, passed through the plates and wings and wall of the trunk in the form of construction

in which the device is shown applied in Fig. 4, while as shown in Fig. 5 the rivets pass only through the plate and wall of the trunk. 55 In order that complete protection may be furnished to each corner of such construction, the metallic plates are extended a short distance over or around all three sides thereof. To illustrate, each one used at the top corners is extended a short distance over the top and at each side and end to which it is applied, and each one used at the bottom corners is extended a short distance under the bottom and at each side and end to which it is applied. 65 The inner plate has a flat central portion, against which a corresponding flat face on the cushion fits, and the corner of the trunk is formed or cut away to present a flat bearing-face for the inner plate. The outer plate 70 has a central opening for the projection of the acting portion of the cushion, with a bead or flange around the periphery of the opening. The two plates constitute a clamp, by means of which and the wings of the cushion 75 the cushion is held in place. The flat faces of the cushion and inner plate furnish a bearing-surface for the cushion in use, and this, in connection with the support had by the wings and the outer plate, results in an attachment that is yielding, strong, and durable and which will prevent the cushion from becoming displaced or torn out in use.

The advantages of my invention are that it provides a simple, economical, and efficient 85 yielding device for protecting trunks, sample-cases, and similar constructions against injury resulting from carelessness, rough handling, or other causes and that this yielding device may be made and applied in the manufacture of the construction to which it is applied or made and sold separately therefrom, as desired. When made separately, the protecting devices may be put in the market and sold as ordinary trimmings. 90 95

I claim—

1. In a corner-protecting device, the combination of a yielding cushion having a central ball-shaped top or bearing-face and a wedge-shaped base formed by outwardly-extending wings or projections, an inner rigid plate having a central bearing-face and fitting against the face of the base of the yielding cushion, and an outer rigid plate having pre-

jecting ends crowding into the dividing-line between the top and base of the cushion and fitting over the extended wings increasing the elastic or resilient quality of the ball-shaped top, and means for firmly securing the rigid plates in place and holding the yielding cushion between them, substantially as described.

2. The combination with a trunk, sample-case or other similar article, of a yielding cushion having a central ball-shaped top or bearing-face and a wedge-shaped base formed by outwardly-extending wings or projections, an inner metallic plate having a central bearing and fitting against the face of the base of

the yielding cushion, an outer metallic plate 15 having projecting ends crowding into the dividing-line between the top and the base and fitting over the extending wings increasing the elastic or resilient quality of the ball-shaped top, and bolts or rivets securing the 20 metallic plates to the corner to which the device is applied and firmly securing the yielding cushion in place, substantially as described.

BEN. F. RUBEL.
